(57) **CLAIM**

The ornamental design for an anesthesia machine with animated graphical user interface, as shown and described.

DESCRIPTION

© 2012 Mindray DS USA, Inc. A portion of the disclosure of this patent document contains material to which a claim for copyright is made. The copyright owner has no objection to the facsimile reproduction by anyone of the patent document or the patent disclosure, as it appears in the file or records of the U.S. Patent and Trademark Office, but reserves all other copyright rights whatsoever.

FIG. 1 is a first image in a sequence for an anesthesia machine with an animated graphical user interface showing our new design;

FIG. 2 is a second image thereof; and,

FIG. 3 is a third image thereof.

The appearance of the transitional image sequentially transitions between the images shown in FIGS. 1-3. The process, period, and/or order in which one image transitions to another image forms no part of the claimed design.
